UNITED STATES PATENT OFFICE.

AMOS F. DIXON, OF NEWARK, NEW JERSEY, ASSIGNOR TO WESTERN ELECTRIC COMPANY, OF NEW YORK, N. Y., A CORPORATION OF ILLINOIS.

PRINTING-TELEGRAPH RECEIVER.

1,128,422.

Specification of Letters Patent. Patented Feb. 16, 1915.

Application filed March 19, 1914. Serial No. 825,901.

To all whom it may concern:

Be it known that I, AMOS F. DIXON, a citizen of the United States, residing at Newark, in the county of Essex and State 5 of New Jersey, have invented a certain new and useful Improvement in Printing-Telegraph Receivers, of which the following is a full, clear, concise, and exact description.

This invention relates to printing telegraph receivers of the type employing a rotating current distributor and has for its principal object the production of such a receiver wherein one selection may be retained while another selection is being prepared. To this end, in combination with a rotating current distributor, electromagnetic devices successively influenced through the agency of the distributor and selective apparatus controlled by these devices, are 15 means for so affecting the relations of these parts that one selection may be retained simultaneously with the formation of another.

The above and other objects of the invention will be fully set forth in the following description and claims, and will be more readily understood by reference to the accompanying drawing in which the system of connections is shown diagrammatically, so much of the apparatus as is necessary to a complete understanding being shown in perspective.

This system is an improvement on the system disclosed and claimed in my copending application, Serial No. 795,073, filed October 14, 1913 and is preferably operated by the well known Baudot code of various combinations of five positive and negative impulses, although other codes may be employed without departing from the spirit of this invention. The impulses arrive sequentially, from a distant transmitting station, over the main line L and traverse a polarized relay 1. Relay 1 is provided with an armature 2 joined to a battery 3 and adapted, let it be assumed, to engage a contact 4 only when positive impulses are received by the polarized relay. Contact 4 is connected to a conducting quadrant 5 of a rotary distributor 10. The rotary distributor comprises a rotating arm 11, which is adapted to be rotated in the direction of the arrow by any suitable means and is equipped with a pair of brushes 12 for suc-

cessively uniting the conducting quadrant 55 5 and the conducting segments 15, 16, 17, 18 and 19. After passing the last segment 19, the brushes 12 unite a segment 20 connected to a battery 21 and a sixth segment 22.

For the sake of brevity of description and simplification of the drawing, only one receiving instrument is shown, although each of the quadrants may serve a separate instrument, so that more than one distinct 60 65 message may be transmitted over a single line conductor at the same time.

The conducting segments 15 to 19 inclusive are connected, respectively, to selecting relays 25, 26, 27, 28 and 29 by means 70 of conductors 35, 36, 37, 38 and 39. Each of these selecting relays is provided with two armatures, the upper being joined, respectively, to corresponding selecting magnets 45, 46, 47, 48 and 49, while the lower 75 is adapted, when attracted, to complete a holding circuit as will be presently explained. The sixth segment is connected by a conductor 50 to the armature of a release control relay 51. An overlap relay 52 is 80 provided through whose armature 53 the energizing circuit of the selecting magnets 45 to 49 and the holding circuits of the selecting relays 25 to 29 may be completed. As will be hereinafter explained, this overlap relay 52, by shifting its armature 53, allows the selecting relays 25 to 29 to be energized without affecting the corresponding selecting magnets 45 to 49, so that while the magnets are held in one combination, the 85 90 relays may be preparing for the production of a new combination.

The printer proper comprises a type wheel 55, on which the characters appear in a double row, and which is carried by a rotatable 95 shaft 56. The rotation of the shaft 56 may be effected by any desired means as, for example, a spring or motor. Arranged concentrically about the type shaft 56 are five notched disks or mechanical selectors 65, 66, 100 67, 68 and 69 adapted to be rotated through a small angle by the corresponding selecting magnets 45 to 49, through the agency of spring-tensioned armatures 70 and arms 71. There is one notch in each of the disks 105 corresponding to each vertical line of characters on the type wheel and one corresponding to each operation, such as spacing, shift-

ing, etc., to be performed. Each of the vertical lines of notches, corresponding to a character to be printed is provided with a spring-tensioned type selecting lever 75 which is adapted, under certain conditions to be hereinafter explained, to be engaged by a contact or stop arm 76 carried by the type shaft 56. The vertical lines of notches representing other operations than type selection are also provided with spring-tensioned levers adapted to control circuit connections, whereby electromagnetic devices for performing the desired function are energized, as hereinafter described.

15 When the armatures of the selecting magnets are attracted, the corresponding selecting disks are rotated, and whenever one or more of the disks are moved so that a continuous vertical line of notches is presented to one of the type or operation selecting levers, the spring thereof tends to force the centrally projecting end of the corresponding lever upwardly into a position to engage the rotating arm 76 or tends to cause 20 the formation of the proper circuit conditions. The type wheel may thereby be arrested in a position to present any desired character to the printing platen, or the proper electromagnetic device may be set 25 in motion to space, shift the type wheel, reset the paper carriage, feed the paper from line to line, or accomplish any other operation which it is found desirable for a receiving printer to perform. The type 30 and operation selecting levers are normally held out of engagement with the selecting disks 65 to 69, and, after the completion of a cycle of operations, are restored to their normal position by a pair of release levers 35 40 adapted to be controlled by a pair of release magnets 86 and springs 87. Normally, the springs 87 cause the circular shaped centrally projecting ends of release levers 85 to depress all of the selecting levers, but when the release magnets 86 are 45 energized, the magnetic pull overcomes the spring tension, and the centrally projecting ends of release levers 85 are elevated. This movement releases all of the selecting levers, 50 one only of which, due to its coincidence with a line of notches, may move a sufficient distance to initiate the performance of the desired function.

The rotation of the arm 11 is so timed, 55 by any of the means well known in the art, that when the first impulse of a combination arriving from a distant transmitting station is acting on polarized relay 1, the pair of brushes 12 carried thereby are bridging 60 conducting quadrant 5 and segment 15; when the second impulse is on relay 1, the brushes are bridging conducting quadrant 5 and segment 16, and so on for the entire number of impulses for each selection. 65 After the arrival of the fifth impulse, seg-

ments 20 and 22 are bridged, whereupon the operation of the printer proper is initiated, as will be hereinafter described.

After the receipt of each of the impulses over the line L, the armature 2 of polarized relay 1 will, depending upon whether or not the impulse is positive, be found in or out of engagement with contact 4, and consequently battery 3 will or will not be connected to the corresponding segment 15 to 75 19. When the impulses are positive, the current from grounded battery 3 flows through contact 4, arm 11, brushes 12, corresponding segments 15 to 19, corresponding conductors 35 to 39, and corresponding selecting relays 25 to 29, and from thence by a conductor 90, through release control relay 51, conductor 91, contact 92 and contact 93 to ground. The circuits just traced cause the proper selecting relays 25 to 29 85 to attract both of their armatures. The upper armatures cause the energization of the corresponding selecting magnets 45 to 49 by completing the following circuits, grounded batteries 100, selecting magnets 45 90 to 49, corresponding upper armatures of selecting relays 25 to 29, conductor 101, and back contact and armature of overlap relay 52 to ground. The lower armatures of the chosen selecting relays 25 to 29 close 95 holding circuits therefor from grounded batteries 105, conductor 90, release control relay 51, conductor 91, contacts 92 and 93 to ground. It is, therefore, readily apparent that whenever one or more positive current impulses are included in the combination of five impulses, the release control relay 51, the proper selecting relays 25 to 29 and their associated selecting magnets 45 to 49 are energized and locked up through the 100 circuits previously traced. The energizing of certain of the selecting magnets 45 to 49 has, through the agency of their armatures 70 and arms 71, produced a slight rotation of the corresponding selecting disks 105 65 to 69, which brings about the presentation of a continuous row of the notches therein before the selecting lever controlling the desired character or operation.

Let it be assumed, for example, that a 115 combination of impulses has been received which caused a movement of disks 65 to 69 such that a continuous vertical row of notches is presented before a lever 75 representing some character in the upper row on the type wheel. With the apparatus in this condition, the rotating arm 11 carries the brushes 12 to segments 20 and 22 and a circuit is completed from grounded battery 21, segments 20 and 22, conductor 50, armature and front contact of release control relay 51, release relay 110, conductors 111 and 112 to ground through the back contact and armature of clear-out relay 115. Release relay 110 attracts its armature completing a 120 125 130

locking circuit for itself and an energizing circuit for the release magnets 86 as follows: ground, armature and back contact of clear-out relay 115, conductors 112 and 111, winding, front contact and armature of release relay 110, conductors 116 and 117, to release magnets 86 and grounded batteries 118. Thereupon, release magnets 86 elevate the centrally projecting ends of release levers 85 against the tension of springs 87, whereupon the type selecting lever 75, before which a continuous vertical line of notches is presented, raises its inner end into a position to engage the arm 76 carried by the type shaft. The movement of one of the release levers 85 also causes the disengagement of contacts 92 and 93 and the engagement of contact 93 and a contact 125. It also causes the engagement of contacts 126 and 127. The disengagement of contacts 92 and 93 opens the previously traced holding circuits for the operated selecting relays 25 to 29 and, consequently, also that of the corresponding selecting magnets 45 to 49. The engagement of contacts 93 and 125 closes an energizing circuit for the overlap relay 52, from grounded battery 130, through conductor 131 and contacts 125 and 93 to ground. Overlap relay 52 thereupon moves its armature 53 from the back to the front contact. The armatures 70 of the operated selecting magnets and the rotated disks 65 to 69 cannot, at this time, return to normal, because of the selected and now elevated lever 75 being interposed in the notches of the disks to hold them in their off-normal position. The armatures of the operated selecting relays 25 to 29, may, however, return to normal and consequently can be again selectively energized through the instrumentality of impulses from line L acting upon relay 1. The circuits for causing such energization does not, as in the first instance, pass through contacts 92 and 93, since they are separated, but obtain ground connections through the front contact and armature 53 of the overlap relay 52. Neither can this subsequent operation of certain of the selecting relays 25 to 29 disturb, in any way, the previous setting of magnets 45 to 49 and disks 65 to 69, because the energizing circuits for the selecting magnets which pass through the upper armatures of the selecting relays are open at the back contact of the overlap relay 52. When, however, after the completion of the printing, the overlap relay 52 is deenergized, as hereinafter described, the circuits for such of the selecting magnets 45 to 49 as have been prepared by their relays 25 to 29 will be completed at the back contact of overlap relay 52 and the corresponding disks 65 to 69 will be rotated. From this explanation it will be readily apparent that a certain operative arrangement of the selecting disks

65 to 69 may be retained while the selecting of another combination is being prepared.

The engagement of contacts 126 and 127 completes a circuit from ground thereat, through conductor 132, start control relay 133 to grounded battery 134. Start control relay 133 draws up its armature and completes a circuit for the starter magnet 135 from grounded armature and back contact of clear-out relay 115, conductors 112 and 140, front contact and armature of start control relay 133, starter magnet 135, conductor 141, fixed contact 142 and movable contact 143 to grounded battery 145. Starter magnet 135 becomes energized and actuates a stop (not shown) to allow shaft 56 to rotate. Shaft 56 rotates, in the direction of the arrow, until stop 76 engages the elevated inner end of the selected lever 75, whereupon it is arrested with the desired character on the type wheel 55 in position to be impressed upon the paper by the printing platen. The engagement of arm 76 and lever 75 also completes a circuit from grounded battery 150, clear-out relay 115, conductors 151 and 152, operating winding of space-lock relay 153, printing magnet 155, arm 76 and lever 75 to ground. Printing magnet 155, space-lock relay 153 and clear-out relay 115 are energized. Printing magnet 155, by means of a platen (not shown), presses the paper against type wheel 55 and the selected character is printed. Space-lock relay 153 pulls up both its armatures, completing a holding circuit for itself and an energizing circuit for the spacer magnet 156. Spacer magnet 156 actuates mechanism (not shown) for moving the paper to present a clean surface to the type wheel. It also causes the separation of contacts 157 which causes the opening of the circuit through the holding winding of the space-lock relay 153. Clear-out relay 115 in attracting its armature, opens the previously traced circuits for the starter magnet 135, release relay 110 and release magnets 86. Release levers 85 are depressed by springs 87, whereupon all of the selecting levers including the one engaged by arm 76 are lowered and the circuit through the printing magnet 155, space-lock relay 153 and clear-out relay 115 is interrupted. Contacts 126 and 127 are separated, opening the circuit for the start control relay 133. Contact 93 is again engaged by contact 92 and then separated from contact 125 which causes the opening of the circuit for the overlap relay 52 and the reestablishment of the first traced energizing circuits for the selecting relays 25 to 29. The deenergization of overlap relay 52 opens the secondary circuits for selecting relays 25 to 29 and reestablishes the ground connection for energizing circuits for selecting magnets 45 to 49. One character has now been printed,

the paper spaced for the receipt of the next, and all of the apparatus returned to normal.

In order to space without printing, a combination of impulses is required which will cause the actuation of such selecting relays, magnets and disks that a continuous row of notches is presented to the selecting lever controlling spacing contacts 160. This causes the energization of the space-lock and clear-out relays, the former effecting the spacing operation and the latter the returning of all the apparatus to normal as hereinbefore described. The feeding of the paper from line to line is produced by the selection and transfer of feed contact 143 from contact 142 to contact 161. Such transfer opens the circuit of the start magnet 135 to insure the non-rotation of the type wheel and causes the energization of feed magnet 162. Feed magnet 162 causes the operation of mechanism (not shown) for feeding the paper and closes an energizing circuit for the clear-cut relay 115, whose operation, as hereinbefore explained, causes the apparatus to return to normal. The type wheel, as before stated, contains two horizontal rows of characters, the upper of which is normally in printing position. In order, therefore, to print a character from the bottom row, it is necessary to shift or elevate the type wheel. This is accomplished by a combination of impulses which will produce the engagement of shift contacts 164. The engagement of these contacts causes the energization of a shifting magnet 165 by a circuit which includes the normally closed unshift contacts 166 and 167 and clear-out relay 115, whereupon mechanism (not shown) shifts the type wheel and the selecting apparatus is returned to normal. It will be noted that the shift magnet in attracting its armature prepares a holding circuit for itself from grounded battery 170, through the unshift contacts 166 and 167. After once being shifted, therefore, characters will be selected from the bottom row until impulses are received to open unshift contacts 166 and 167. This opens the holding circuit for shift magnet 165 and the engagement of contact 167

and 171 operates the clear-out relay 115. Carriage contacts 172 when selected and operated, cause the energization of carriage return magnet 173, which by means of mechanism (not shown) effects the return of the paper carriage to the beginning of a line of print. This magnet also completes a holding circuit for itself through its armature, which circuit is broken at contacts 174 when the carriage has completed its return travel. In the spacing, feeding, etc., operations, precisely as in the selecting and printing of a character, one selection may be retained while the preliminary selecting of the subsequent operation or character is taking place.

What is claimed is:

1. In a printing telegraph receiver the combination of a rotary current distributor, selecting relays controlled thereby, selecting magnets controlled by said relays, energizing and holding circuits for said relays and magnets, and means for altering the conditions of said energizing and holding circuits, whereby said relays may be selected without affecting said magnets.

2. A printing telegraph receiver comprising a plurality of members from which one is to be selected, a plurality of mechanical selectors for completing such selection, a plurality of magnets controlling said selectors, selecting relays for causing the actuation of said magnets, a rotary current distributor, actuating circuits for said relays and said magnets, release means co-operating with said distributor to allow the operation of said selected member, overlap means controlled by said release means to alter said actuating circuits, and means co-operating with said member to cause said overlap means to restore normal circuit conditions.

In witness whereof, I hereunto subscribe my name this 17th day of March A. D., 1914.

AMOS F. DIXON.
